UNITED STATES PATENT OFFICE

2,439,661

SYSTEM FOR TRUE AMPLITUDE MODULATION OF RADIO WAVES

Donald B. Keever, Colfax, N. C.

Application October 17, 1947, Serial No. 780,315

10 Claims. (Cl. 179—171.5)

1

The present invention relates to modulation systems and it consists in the combinations, constructions and arrangements of parts herein described and claimed.

An object of the invention is to reduce the channel width required for the transmission of an amplitude-modulated wave.

A further object of the invention is the reduction of the required channel width by the substantially complete elimination of side bands leaving only a wave of varying amplitude and of single constant frequency.

Other and further objects will become apparent upon reading the following specification together with the accompanying drawings forming a part hereof.

Referring to the drawing:

Figure 1 is a symbolic block diagram of an embodiment of the invention, and

Figure 2 is a schematic circuit diagram illustrating an arrangement in accordance with the diagram of Figure 1.

Referring to Figure 1, the modulating frequencies are shown as originating at a microphone 11 and are applied to the input of a speech amplifier 12. Any other suitable source of modulating frequencies may be used, however. The output of the amplifier 12 is connected to a modulator 13 which is connected to produce amplitude modulation of carrier currents passing through modulated amplifier 14. The carrier currents are derived from a stable oscillator 15 or any other suitable source of constant frequency carrier current.

The amplitude-modulated output of amplifier 14, together with the usual side-bands resulting from the modulation is applied to a further amplifier 16 whose characteristics are substantially linear. The output of amplifier 16 is divided into two portions, one of which is passed through a limiter 17 indicated as being of the clipper type. The limiter 17 removes the amplitude modulations leaving a modulated current of constant amplitude which varies in frequency in accordance with the side-band frequencies.

The discriminator 18 is of the usual type and the magnitude of the output voltage thereof varies in accordance with the amount of deviation of the frequency from a predetermined center frequency of the instantaneous phase relationships being determined by the direction of such deviation.

Connected to the output of the discriminator 18 is an audio frequency amplifier 19 whose output is sufficient to modulate amplifier 20 to the same degree as the degree of modulation produced

2

at the amplifier 14. Modulated amplifier 20 is substantially identical in all respects to the amplifier 14 and modulates the output of stable oscillator 21, except for its output frequency, is identical to the stable oscillator 15. Both oscillators may be of different harmonics selected from a common frequency multiplying system or they may take any other desired form which will provide the required degree of frequency stability.

The outputs of amplifier 16 and of modulated amplifier 20 are combined in a mixer or heterodyne converter 22. The output of mixer 22 will contain both the sum and the difference frequencies produced by the two inputs and a filter 23 may be provided to select either the sum or the difference frequency, if required. The filter 23 will not be necessary, however, if the characteristics of linear driver stage 24 and power amplifier 25 are sufficiently selective.

The driver stage 24 and power amplifier 25 are of conventional type and serve to provide the desired amount of output energy for radiation at the antenna 26 or for transmission by any other desired means.

The amplifier 19 is provided with a gain control so that its amplification may be adjusted for balancing purposes.

Referring to Figure 2 in which the circuits of the various elements shown in Figure 1 are illustrated in greater detail, the stable oscillator 15 is shown by way of example as comprising a crystal 15—01 connected to a triode 15—02 to provide a crystal controlled oscillator of conventional type.

The oscillator 21 is similar in all respects to the oscillator 15 except for the frequency of operation.

The microphone 11 is connected to the amplifier 12 which comprises a triode 12—01 associated with a volume control 12—02 in conventional manner to amplify the currents generated in the microphone 11.

The output of the speech amplifier 12 is shown 45 capacitatively coupled to a further amplifier or modulator stage 13 which raises the level to a point sufficient to produce plate modulation in stage 14. The modulator 13 is shown as comprising a tetrode 13—01 coupled by a transformer 13—02 to the modulated amplifier 14. The amplifier 14 is illustrated as comprising a tetrode 14—01 operatively associated with a tuned output transformer 14—02 to which the modulated anode potential from the transformer 13—02 is applied. A desired amount of modulated out-

put voltage is taken from an adjustable tap 14-03 and applied through a coupling capacitor 16-02 to the control grid of tetrode 16-01 of the linear amplifier stage 16.

The tuned output transformer 16-03 is shown 5 provided with two secondaries 16-04 and 16-05. The secondary 16-04 is directly connected to the input of the mixed 22 which is shown as being of the balanced type.

The other secondary is connected to the input 10 transformer 17-03 of the clipper limiter stage 17 which comprises the two oppositely connected diodes 17-01 and 17-02 which are connected in multiple and in series with suitable sources of biasing potential indicated as batteries 17-04 and 17-05. For symmetrical limiting, the potentials of batteries 17-04 and 17-05 are substantially equal and they are applied to their respective diodes with a polarity which will prevent conduction until the biasing potential is exceeded. When the instantaneous voltage in either direction exceeds the biasing potential of the corresponding diode, conduction will take place and the excess voltage will be limited by current flow 15 through one of the diodes.

The output of the limiter 17 passes to the input 20 of the discriminator 18 which is of the conventional Travis type and comprises the diodes 18-02 and 18-03. This discriminator, which is a well-known device in the art of frequency-modulation, converts changes in frequency into changes in amplitude, and these in turn are passed on to the tetrode amplifier stage 19 which is similar to the amplifier stage 13, its output being sufficient to plate modulate stage 20.

The output of the oscillator 21, after modulation in stage 20, is applied to the center tap connection 22-01 of the balanced mixer 22 where it is combined with the output of the amplifier 16. The output of the mixer 22 is connected through the filter 23, if used, to a concentric transmission line 30 to the driver stage 24 and the power amplifier stage 25 from which the signals are applied to the antenna for radiation.

The circuits shown for each of the various 45 stages are conventional in character and are well-known in the art and other equivalent circuits of similar character may be selected as desired to meet any particular set of operating conditions encountered in practicing the invention.

In operation, the modulated output of amplifier 14 is carried through to the mixer 22 and consists of the carrier frequency generated by the oscillator 15 together with the side-band frequencies produced by the modulation. A portion 55 of the carrier frequency of the oscillator 15 together with the side-band frequencies is tapped off at the amplifier 16 and is limited in the clipper 17 so that the amplitude modulation is substantially completely eliminated, leaving a signal modulated in frequency in accordance with the side-band frequencies.

The discriminator 18 has its center frequency 60 adjusted to coincide with the frequency of the oscillator 15 so that the deviation from the carrier frequency is the factor which causes an output to be obtained from the discriminator, the magnitude of the output being substantially proportional to the amount of such deviation, but the particular frequencies remaining unchanged. The current thus produced is modulated upon a carrier frequency derived from the oscillator 21 and the modulated output contains side-bands 65 together with the carrier frequency which are applied to the mixer 22.

In the mixer 22, the two frequencies produced by the oscillators 15 and 22 are combined together with the modulations impressed thereon. One of these will consist of the usual amplitude modulated carrier and the side-bands. The other will consist of modulation products whose instantaneous magnitudes are in direct proportion, not to the instantaneous magnitudes of the other side-band components, but to their frequency deviations from the carrier. By applying these components in such phase relationship as to cancel the side-band components of the direct channel from amplifier 16, and by adjusting their relative magnitudes by means of the amplifier adjustments, the side-band frequencies will be cancelled out leaving only a true amplitude modulated carrier without the side-bands.

What is claimed is:

1. A modulation system comprising a source of signalling currents, a first source of carrier frequency, modulating means arranged to modulate the first carrier source with the signalling currents, limiting means responsive to a portion of the modulated currents and arranged to remove amplitude modulation therefrom, frequency discriminating means responsive to the limiting means and disposed to produce an output whose magnitude is substantially proportional to the frequency deviation of the limited currents from the first carrier frequency, a second source of carrier current, further modulating means arranged to modulate the current of the second source with the output currents of the discriminating means, and mixing means disposed to combine the currents of the two modulating means in such degree and in such phase relationship that a modulated current is produced consisting in its entirety of a third carrier frequency modulated in amplitude and unaccompanied by extraneous currents of side-band frequencies.

2. A modulation system as in claim 1, in which the third carrier frequency consists of the sum of said first and second carrier frequencies.

3. A modulation system as in claim 1 in which the third carrier frequency consists of the difference between the first and second carrier frequencies.

4. The method of obtaining a current signal modulated in amplitude alone without accompanying side-band frequencies which consists in the steps of generating a first carrier current of substantially constant frequency, modulating this current with the signalling current, taking a portion of this modulated current and removing the amplitude variations therefrom, attenuating the last-named currents inversely in accordance with their frequency deviations from frequency of the first carrier current, generating a second carrier current of substantially constant frequency, modulating the second carrier current with the attenuated currents, and combining the modulated first and second carrier currents in such degree and in such phase relationship that the combined current consists of a current of a third frequency modulated in amplitude alone and unaccompanied by extraneous currents of side-band frequencies.

5. The method set forth in claim 4 in which the first and second modulated currents are so combined that the third current has a frequency equal to the sum of the first and second frequencies.

6. The method of obtaining a current signal set forth in claim 4 in which the first and second modulated currents are so combined that the

third current has a frequency equal to the difference between the first and second frequencies.

7. A modulation system comprising a source of signalling currents, a first source of carrier frequency, amplitude modulating means arranged to modulate the first carrier source with the signalling currents, limiting means responsive to a portion of the modulated currents and arranged to remove amplitude modulation therefrom, frequency discriminating means responsive to the limiting means and disposed to produce an output whose magnitude is substantially proportional to the frequency deviation of the limited currents from the first carrier frequency, a second source of carrier current, further amplitude modulating means arranged to modulate the current of the second source with the output currents of the discriminating means, and mixing means disposed to combine the currents of the two modulating means in such degree and in such phase relationship that a modulated current is produced consisting in its entirety of a third carrier frequency modulated in amplitude and unaccompanied by extraneous currents of side-band frequencies.

8. A modulation system comprising a source of signalling currents, a first source of carrier frequency, amplitude modulating means arranged to modulate the first carrier source with the signalling currents, clipper type limiting means responsive to a portion of the modulated currents and arranged to remove amplitude modulation therefrom, frequency discriminating means re-

sponsive to the limiting means and disposed to produce an output whose magnitude is substantially proportional to the frequency deviation of the limited currents from the first carrier frequency, a second source of carrier current, further amplitude modulating means arranged to modulate the current of the second source with the output currents of the discriminating means, and balanced mixing means disposed to combine the currents of the two modulating means in such degree and in such phase relationship that a modulated current is produced consisting in its entirety of a third carrier frequency modulated in amplitude and unaccompanied by extraneous currents of side-band frequencies.

9. A modulation system as in claim 8 in which the third carrier frequency consists of the sum of said first and second carrier frequencies.

10. A modulation system as in claim 8 in which the third carrier frequency consists of the difference between the first and second carrier frequencies.
